CLAIM

The ornamental design for a lower rear bumper for a vehicle, as shown and described.

DESCRIPTION

FIG. 1 is a right front perspective view of a lower rear bumper for a vehicle according to the present invention.

FIG. 2 is a left front perspective view of the lower rear bumper for a vehicle shown in FIG. 1.

FIG. 3 is a right rear perspective view thereof.

FIG. 4 is a left rear perspective view thereof.

FIG. 5 is a front view thereof.

FIG. 6 is a rear view thereof.

FIG. 7 is a right left side view thereof.

FIG. 8 is a left side view thereof.

FIG. 9 is a top view thereof.

FIG. 10 is a bottom view thereof; and,

FIG. 11 is a right front perspective view of the lower rear bumper for a vehicle shown in FIGS. 1-10, mounted on a vehicle, with the rest of the vehicle shown in de-emphasized and half-tone portions so as to illustrate environmental structure.

These portions form no part of the claimed design. More particularly, in FIG. 11, the inventive lower rear bumper for a vehicle is shown within the broken line, and the elements
